UNITED STATES PATENT OFFICE.

LEONARD HEALD, OF MONTREAL, QUEBEC, CANADA.

HYDRAULIC MECHANISM FOR RAILWAY DEVICES.

1,239,007.

Specification of Letters Patent. Patented Sept. 4, 1917.

Application filed April 20, 1914. Serial No. 833,185.

To all whom it may concern:

Be it known that I, LEONARD HEALD, of the city of Montreal, Province of Quebec, Canada, have invented certain new and useful Improvements in Hydraulic Mechanisms for Railway Devices; and I do hereby declare that the following is a full, clear, and exact description of same.

This invention relates particularly to a hydraulically operated mechanism which is acted upon by a train, vehicle or the like run upon tracks or can be adapted to be operated by hand or the dislocation of tracks to automatically operate brakes, signals or other railroad devices.

One of the objects of my invention is to provide means whereby trains traveling at a high speed can be brought to rest within a comparatively short distance and to obviate the long slide of the train which is caused by trains running at high speed along smooth rails and which cannot be overcome by brakes affixed to the train itself.

Another object is to provide means for positively reducing the speed of trains at desired points along the route.

Another object is to provide an automatically operated mechanism for applying brakes, setting signals or operating switches and gates.

Another object is to provide a brake at the side of a railroad track and automatic means for first setting the brake and subsequently applying same.

35 A further object is to provide a brake setting device which is adapted to be engaged by a train to automatically set the brake and means for maintaining the latter in such position for a predetermined period, independently of the action of the train.

Still further objects are to provide, first devices for setting the brake in the event of any disorder in the hydraulic mechanism or tracks; second, means for intermittently reducing the operating pressure in an automatic manner whereby vehicles can be brought to rest within a predetermined distance; third, an arrangement whereby the brake operating mechanism may be made 50 unresponsive to the action of a train upon the setting device; and fourth, means where-

by the setting device can be operated by hand.

The objects and advantages of this invention will be hereinafter more fully described and pointed out in the claims.

For full comprehension however of my invention reference should be had to the accompanying drawings forming a part of this specification, in which similar reference characters indicate the same parts and wherein:

Figure 1 is a view, partly in side elevation and partly in vertical section of the brake setting device;

Fig. 2 is a detail plan of the setting device;

Fig. 3 is an enlarged section on line 3—3 Fig. 2 illustrating the normal position of the setting device;

Fig. 4 is a view similar to Fig. 3 and showing the operative position of the setting device;

Fig. 5 is a view partly in side elevation and partly in vertical section of the brake operating mechanism.

Fig. 6 is a horizontal section of one of the casings and taken on line 6—6 Fig. 5.

Fig. 7 is a plan view of the brake mechanism as applied to one of the rails.

Fig. 8 is a vertical section on line 8—8 Fig. 5.

Fig. 9 is an enlarged detail section on line 9—9 Fig. 8.

Fig. 10 is a view illustrating a series of brakes and

Fig. 11 is a detail of the hand setting device.

Fig. 12 is a plan of the track disorganizing device.

Fig. 13 is a detail of the device for the non-operating of the setting device.

Fig. 14 is a detail of the device for operating the setting device on the failure or removal of a part or parts of the setting device.

Fig. 15 is a detail of the valve to govern the setting device of the following brake when the brakes are set in series.

Fig. 16 is a detail of the device to be attached to a part or parts of the mechanism to insure a setting of the device on the breakage of any aforesaid part or parts.

The present hydraulic mechanism may be of any preferred construction and applied to any railroad device such as brakes, signals, gates, and switches and the like but it is 5 particularly adapted to brakes and I will now describe it in connection with same.

Briefly my invention comprises contact members located beside the rails and adapted to be brought into engagement with a 10 train; an automatic hydraulic mechanism for operating the contact members and a device located at some distance from the contact members and adapted, when engaged by a train to set said members in an operative 15 position, and the subsequent engagement of a train with the contact members automatically applying same.

My preferred construction is shown by the accompanying drawings wherein 2 indicates 20 a piston casing suitably located beneath one of the rails 3 and containing a piston rod 4 which extends up through the top of the casing to the rail 3. A partition 5 divides the casing 2 into a top compressed air chamber and a bottom fluid chamber, the piston rod carrying a head 6 in the fluid chamber and a second head 7 in the air chamber.

The piston 4 in the casing 2 is adapted to be forced down by the action of a train 30 on some compressible means connected to the piston and which may be as shown in the drawings wherein the rail 3 is divided into two separate rail portions 8 and 9 respectively which have the base flanges removed 35 and are pivoted at 10 adjacent to the main portions of the rail. The rail portions 8 and 9 extend inwardly toward each other to a point above the rod 4 the top of which is slotted as at 11 to receive such free ends. The pivoted rail portions are inclined so 40 that their free inner ends are normally elevated above the horizontal line of the rail as seen in Fig. 1 and when a train passes thereover, are depressed and force the piston down, the free ends of the rail portions practically abutting in their depressed 45 position. The compressible portions are braced and guided by the brackets 12 carrying pins 13 passed through curved slots 14 in the rail portions.

The downward movement of the piston head 6 forces the fluid from the casing 2 through a pipe 14^a into another hydraulic piston casing 15 which is operatively connected to the brake proper and is adapted 55 to set the same in operative position, as will be presently described.

The brake is adapted to be applied along the full length of the train and for this 60 reason the brake proper and its operating mechanism are installed in series of any desired number, but for the sake of clearness and to avoid repetition I shall now only describe one brake mechanism in detail, the

connection of such brake in series to be explained later.

The brake proper comprises a member at each side of the rail, the outside member consisting of a plate 16 of suitable length and supported at its ends by extensions 17 and 17^a terminating in curved portions 18 loosely resting upon plates 19 at the side of the rail. The inside member is of similar construction to the outside member but to avoid interference with the members of the 75 trucks of passing trains, this inside member is of lesser height as seen in Fig. 8.

The plates 16 are applied to each rail and in normal position the inner and outer plates are spaced from each other for their full 80 length a sufficient distance between them being maintained to permit of the passing of the wheels of a train between them without interference. Arms 20, 20^a and 21, 21^a are provided to uphold and operate the 85 plates, the lower ends of these arms being pivoted to brackets 22 at a point 23 some distance below the rails and to one side of and above the casing 15. The arms extend upwardly and outwardly, the upper ends 90 having a sliding connection with the plates by means of blocks 24 carried by the arms and slidably located in longitudinal grooves 25 formed in the plates. Ball or other bearings 26 are provided between the blocks 24 95 and the walls of the grooves.

One or more contact faces or rails 27 are formed on the inner sides of the plates 16 and these contact faces are adapted when the 100 brake is set as hereinafter described, to engage with similar faces or rails 28 (see Fig. 8) carried by wheel engaging shoes 29 attached to the lower free ends of the U-shaped brackets 30 suspended from the body or other suitable part 31 of an engine or car. 105 The brackets are formed of springy material and straddle the wheels 32 of the said engine or car, the arms of the brackets being normally spread apart and the shoes 29 held out of engagement with the wheels by 110 springs 33 bearing between such arms.

The casing 15 contains a piston 34, the rod 35 of which is formed with teeth to constitute a rack and extends up through the top of the casing and engages with a gear 115 wheel 36 the normal fluid level in the casing 15 being such that the gear wheel 36 engages during the maintenance of such level about mid-way its length of the rack for a purpose to be presently explained. The 120 gear wheel 36 is mounted upon a shaft which also carries drums 37 and 38 the drums and gear wheel being inclosed by a housing 39 upon the top of the casing 15. The drum 37 has one end of a cable 40 attached thereto, the other end of the cable being divided into two lengths 40^a and 40^b which are passed in opposite directions over a pulley 41 be-

tween the pivoted ends of the arms 20 and 20^a and respectively attached to such arms at points preferably about midway of the lengths of the latter. The other drum 36 5 is similarly connected to the arms 21, 21^a by a cable 42 having one end divided as at 42^a 42^b.

The rail portions 8 and 9 and casing 2 comprising the setting device are located at 10 some distance beyond the brake proper so that a train after passing through the latter will engage with the rail portions and depress the piston in the casing 2; the fluid forced from the casing 2 will cause the fluid 15 level in casing 15 and with it the piston 34 to rise and by reason of the engagement between the rod 35 and the gear wheel 36, wind the cables 40 and 42 upon their respective drums and thus cause the arms 20, 20^a 20 and 21, 21^a at the front ends of the plates attached thereto to move toward each other, the plates 16 rocking on the curved portions 18. The action just described of the arms causes the front portion only of the plates 25 to move inwardly toward each other and thus set the brakes in operative position, presenting a V-shaped inclosure on each rail, see dotted lines Fig. 7.

The V-shaped inclosure is maintained for 30 a predetermined time and independently of the action of the train upon the setting device by the provision of a valve 43 at the opening of the pipe 14^a into the casing 15, this valve being provided with a drainage 35 port 44 to gradually drain the excess fluid from the casing 15 back to the casing 2 and permit the piston to drop to its normal level after the train has passed over the rail portions 8 and 9. The raising of the piston 4 40 and the positioning of the inner ends of the rail portions are automatically accomplished by the return of the fluid to the casing and particularly by the expansion of the air which was compressed between the head 7 45 and the partition 5 during the downward movement of the piston.

The setting of the brake is indicated by a signal arm 46 carrying a gear wheel 47 and operated by a rack 48 extending down 50 through a pipe 49 to a cylinder 50 where the end of the rack is enlarged as at 51. A branch pipe 52 leads from the pipe 14^a to the cylinder 50 and when there is pressure in the pipe 14^a such pressure is transmitted to the cylinder 50 and the rack 48 is raised to operate the signal.

I have provided means whereby the brake 60 will be set in the event of any dislocation of the rail portions 8 and 9 or if any obstruction prevents the depression of such members or if any portion of the ordinary track is broken or disarranged.

The above indicated means consist of a presser piece 54, preferably curved on its

upper surface, extending between the free 65 ends of the portions 8 and 9 and located in longitudinal extending vertical slots 55 formed in such free ends, said slots presenting stops 56 limiting the downward movement of the presser piece. The slots 70 55 are enlarged to form shoulders 55^a which are located at the sides of the presser piece and rounded as shown particularly in Figs. 3 and 4.

The upper portion of the piston rod 4 is 75 hollowed out as at 57 and has side openings 58 leading from the hollowed out space. A block 59 is located at the bottom of the space 57 and rests upon a spring 60, the upper portion of the block being reduced to 80 form shoulders 61. The spring 60 yieldingly maintains the block in its normal raised position. The underside of the presser piece 54 is formed with a groove 62 at either side thereof, each groove accommodating 85 the upper ends of a pair of arms 63 which are slidably attached thereto by means of pins 63^a passed through a longitudinal slot 63^b formed in the contact piece. The arms extend downwardly adjacent to 90 and in front of the shoulders 55^a into the space 57 and are connected to the block 59 by links 64 and 65 which have a slotted connection 59^a with the arms 63 and normally hold same out beyond the shoulders 95 61. The links 65 are attached to the block 59 at a point above the links 64 and are upwardly inclined and longer than the latter. Pawls 66 carried by the rail portions in and near the bottom of the slots 55 normally engage in notches 67 in the arms 63. 100

In the under surface of each rail portion and adjacent to the slots 55 a depression 68 is formed, inclosing a central boss 69 having a slight depression 70. Arms 71 having 105 their upper rounded ends in the depressions 70 extend downwardly from the rail portions on opposite sides of the piston rod and are pivoted in a transverse slot 73 formed through the piston rod. The inner ends of 110 the levers are attached by a line 74, to a weighted valve 75 controlling and normally held to close a duct 76 extending from the bottom of the piston rod 4 up through the same to an outlet 77 located at a point maintained at all times above the top of the casing. Loose arms 78 have their inner ends located in the side openings 58 and beneath the lower ends of the arms 63, extending 115 from the openings into slots 79 in the inner 120 side of the arms 71. Flat springs 80 fastened to the underside of the rail portions 8 and 9 bear against the outer side of such arms 71.

As the rail portions 8 and 9 are depressed 125 under normal conditions the arc described by their free ends causes the shoulders 55^a to force the arms 63 inwardly toward each

other, the pins 63^a sliding in the slots 63^b, and any resistance offered by the link connections 64 and 65 to this inward movement of the arms, being overcome by the upward 5 inclination of the links 65. The arms 63 and the presser piece are also moved downwardly by the engagement of the pawls 66 with the notches 67 in the arms. This movement of the arms 63 brings them out of the 10 vertical line with arms 78 and into engagement with the shoulders 61 of the block 59, the yielding support of which latter, enables sufficient downward movement of the arms to completely lower the presser piece within 15 the slots 55 as shown in Fig. 4.

In the event of the rail portions becoming obstructed so as to prevent the depression thereof the presser piece is engaged by the wheel of the passing train or the like and 20 as seen in the dotted lines Fig. 14 depressed. The arms 63 are also depressed but are not engaged by the now stationary shoulders 55^a and are thereby permitted to move straight down and engage with the loose 25 arms 78, forcing the latter outward, and thus dislodging the upper ends of the arms 71 from the bosses 69 and into the depressions 68 to permit of a limited movement of the levers 72, which allows the weighted 30 valve to open the duct 76.

The construction of the whole mechanism is based on the principle of balance. The fluid is a fulcrum; each piston theoretically counterbalances with another though each 35 piston is not necessarily of equal weight, because each piston has auxiliaries assisting in the balance, viz., piston 6 Fig. 1 is assisted by the compression chamber in head of cylinder 2, to balance piston 34, cylinder 15.

40 The dropping or forcing upward of the piston 34, cylinder 15 does not exert any force whatsoever on the train, nor is it intended to do so. Piston 34, is the communicating link between the setting device and 45 the device to be operated, which may be a gate, signal, switch, roundhouse, brake or other railway mechanism.

The opening of the duct 76 drains the 50 fluid from the casing 15 and causes the piston 34 to move down below its normal level and set the brake, it being here pointed out that the engagement of the rod 35 at a point about midway of its length with the gear wheel 36 provides for the engagement of the 55 upper portion of the rack with the latter, when the piston falls, and the winding of the cables 40 and 42 upon the drums 37 and 38 in an opposite direction to but securing the same result as the previously described 60 winding of the cables by the raising of the piston 34. The cable 88 is slack to allow of sufficient action for the lowering of gate valve 86 during this action.

The removal of any of the parts, for instance the presser piece 54 or the arms 63

will cause the springs 80 to force the lever 71 from the bearings 69 into the depressions 68 with the above result. It being noted 70 arms 78, are directly below arms 63, and their associate parts, in reality arms 63 would rest slightly on the curved part of arms 78, pawls 66 would also engage arms 63. The springs 80, press against levers 71 and thereby arms 78, and so on to arms 63. Should the presser piece 54 be bodily drawn 75 up the resultant action would be that the spring 80 will force lever 71 inward and also arms 78 inward, and as any weakening 80 of the associate parts would cause the weighted head 75 leading to orifice 77, to open and allow the piston 34, Fig. 5, to exert pressure on the fluid and to force fluid up and through orifice 77, thereby allowing the piston 34, to fall sufficiently and bring 85 into action drums 36 and gears 37, and winding cables 40 and 42, this will cause the shoes 16, to assume the set position of V or inclined inwardly at the front of the brake.

Again to take the opposite action to the withdrawal of the presser piece 54, which 90 is that for some reason viz., the packing under the lever rail 8-9 of drift sand, snow, or melting snow, and the resultant formation of ice, the rails 8-9 fail to be depressed. In this case the presser piece 54, will be depressed instead of rails 8-9; it is perfectly 95 obvious that from the construction shown in the drawings that the arms 63, will engage arms 78, and press arms 78 outwardly as shown by the dotted lines, into the recess 100 prepared for same, and the inside angle formed by arms 71 and 72, become larger allowing sufficient play for the weighted valve 75, to uncover the passage leading to 105 orifice 77.

The indicated means for track breaking consists of the track being formed with a passage at its base 207. This passage consists of a suitable conduit 208 to a casing 206. A floating piston 204 receives a center rod with a head 203^a, and is attached slidably at 205 to a floating piston 204, this floating piston 204 allowing for the expansion of fluid in casing 206 and the rail passage 207, without action on the center rod 203, and the beam 200^a. The beam 200^a is pivoted at 201, one end of which connects to cable 192 at 200. The other end is so suspended as to engage and receive the weight of the piston 204 and the rod 205 at 203 and be depressed by same, causing the cable 192 to release spring 191, on the fluid escaping from the passage 207 and the consequent falling of the piston 204 and the rod 203, whose combined weight on the end 110 of lever beam 200 acts on cable 192, and 115 throws the weight upon the catch 191.

I will now describe that which is acted upon by the raising of cable 192. It will 120 be understood from the operation of Fig. 1 125

and Fig. 8 that any downward pressure exerted upon piston 6 Fig. 1, will force the fluid from cylinder 2 along conduit 14, to cylinder 15 also along branch conduit to the back of piston 193, Fig. 5, situated in an annexed chamber 185 placed about midway of cylinder 15. This annexed chamber 185 is normally filled with air. The pressure from cylinder 2 will force piston 193, to compress the air in the annexed chamber 185. On the release of the pressure in the cylinder 2, and the rise of the piston 6, due to the expansion of the air in the head of cylinder 2, there will be a vacuum between the head of piston 6 and the fluid in the cylinder 2.

In filling this vacuum suction will be caused; this suction plus the pressure from the compressed air in front of the piston 193, will return the piston 193 to normal. It will be seen that a valve 197, is placed toward the front part of the annexed chamber 185, and is so placed that a slide valve 187, will when in action slide so as to cover the opening to the valve 197. When the normal action is taking place *i. e.* the pressure as above explained this valve 197, is uncovered and the passage formed by the conduit 196 is free to carry air under compression from the annexed chamber 185. The conduit 196, has arranged at its farther end a spring or gravity catch 198, normally relaxed. The compressed air forces this spring or gravity catch 198, to engage with a slot constructed in a valve 194 which normally closes a passage communicating with the annexed chamber 185, and the cylinder 15; the above is detailed on Fig. 11.

Recapitulation: The piston 6—7 is depressed and the fluid is compressed in the head of the cylinder 2, and the bottom fluid from cylinder 2 is forced to the cylinder 15 and the annexed chamber 185, also the air is forced from the annexed chamber 185 to the catch 198. The resultant of this compression is that the piston 34, of the cylinder 15 is forced upward to engage with the gear 36 and drums 38, so constructed to receive and utilize the power created by the depression of the piston 6 and the catch 198, is also forced to lock the valve 194 to prevent action on same. The removal of the cause of the depression of the piston 6 releases the compression under the head 7, and the piston 7—6 rises and consequently a vacuum is caused between piston 6 and the surface of the fluid. To fill the vacuum suction acts bringing the fluid and the various portions of the mechanism to normal. This completes the ordinary actions.

It may be desired to operate the setting device automatically as when a dislocation, breakage or weakening of tracks takes place, or by hand. It will be seen that at the communication of the cylinder 15, and

the annexed chamber 185, there is placed the aforementioned slide valve 187, constructed of a cylinder beveled at one end to fit closely to a seat prepared at the communication of the cylinder 15, and the annexed chamber 185, the slide valve 187, covers a port 189, constructed on an inner partition separating inlet slide valve 187, and outlet valve 194, the constant pressure exerted by the piston 34, would if left free of action force the valve 187, along the cavity wherein it rests, thereby uncovering the port 189, through which the fluid could obtain access to the annexed chamber 185. To prevent this a spring lock 191, is constructed to operate through the outer casing of the annexed chamber 185, and penetrates a slot in the cylinder slide valve 187, normally holding the valve 187, rigid. It can therefore be understood that should through any cause the lock 191, (*i. e.*, the raising of the cable 192,) be released the slide valve 187, will uncover the port 189. Supposing the spring lock 191, is released and gravity acting on the piston 34, and the gravity pressure communicated to the fluid in the cylinder 15, and so to the slide valve 187, the valve 187, will uncover the port 189, causing the flow of the fluid from the casing 15 into the annexed chamber 185, with the resultant falling of the piston 34 and the setting of the brake, or other railroad device. It will be seen that during this action of filling the chamber 185 with the fluid from cylinder 15, the slide valve 187 covers the entrance to conduit 199. The air contained in the chamber 185 is forced out through the one way outlet valve 190 which is placed farther along from catch 191 on chamber 185. The valve 190 is connected by a bar to the spring catch 191, the spring catch 191 assisting in operating valve 190 and in holding same normally closed.

To bring the mechanism back to normal after the chamber 185 has been filled with fluid from the chamber 15, it is necessary that the piston 6, cylinder 2, be again depressed, which will force the piston 34 upward and also by the action on the piston 193 of the annexed chamber 195 upon the contained fluid, will force the fluid through the valve 194 back to the casing 15, also closing the slide valve 187. The annexed chamber 185, contains a smaller quantity of fluid than will be expelled from the cylinder 2, therefore it will be cleared before cylinder 2 can expel its quota through conduit 14^a, to cylinder 15.

It is a known fact that some fluids, *e. g.*, water, are practically incompressible and when subjected to pressure creates what is known as water hammer. In contrast therefore to the air which is normally contained in the annexed chamber 185, there is now a fluid such as water; this is subjected to pres-

sure from cylinder 2 more or less sudden, the resultant is water-hammer acting upon the slide valve 187, causing it to close and the lock 191 to hold same, also the valve 194 is open, and the fluid or water is forced back to cylinder 15. On the pressure in cylinder 2 being released and the aforementioned suction taking place the piston 193 returns to normal and a needle air valve 195 which is so placed that during part of the sliding of the piston 193 it is covered by piston 193, now opens allowing the annexed chamber 185 to fill with air. It will also be noted that the piston 193, covers valve 190 during the piston's sliding action. The normal is now resumed by the valves and the annexed chamber 185, is again filled with air from valve 195, and resumes the first described action.

20 It may be desired to prevent the setting of the brake when a train passes the setting device, and for this reason I have provided an auxiliary chamber 81 communicating with the fluid chamber of the casing 2 by a pipe 82, and having a second pipe 83 leading therefrom to such fluid chamber, the pipe 83 being provided with a valve 84 controlling the opening from the pipe into casing 2, and being opened by the pressure in the latter chamber 81. The pipe 82 and pipe 14^a are each provided with a gate valve 85 and 86 respectively which are connected by cables 87 and 88 to spools 89 and 90 supported by brackets 91 besides the rail, the cables 88 being partially wound upon the spool 90. The spools 89 and 90 carry upwardly projecting arms 92 and 93 respectively. The cables 87 and 88 are suitably passed over pulleys 94 and connect by a beam 95 weighted by shot or the like and pivoted between its ends as at 96. In normal position the valve 85 is closed and the valve 86 open.

45 One of the said spools is located at either end of the rail portions 8 and 9 and may be spaced any distance therefrom and when desired a contact member 97 carried by the train is lowered so that before the train encounters the setting device it will engage with the arm 92 and wind the cable carried over pulley 94 to permit the valve 85 to open. The beam 95 simultaneously cause the valve 86 to close so that when the train forces the piston in to the casing 2 the fluid 50 in the latter will be forced through the pipe 82 into the auxiliary chamber 81 instead of through pipe 14^a to set the brakes. When the train has passed the setting device the contact member 97 engages with the arm 92 and now winds cable 88 to permit the 55 return of the valves to normal position, the initial movement being facilitated by the weighted beam 95.

60 It will be apparent that the setting device 65 may be so arranged as to be engaged by a

train before instead of after the train has reached the brake mechanism.

When the brakes have been set in V-shape by the passing train as previously described and another train attempts to pass this point 70 before the expiration of the predetermined time, for which the brakes have been set, or maintained in their operative position, the contact faces 28 of the brake shoes 29 enter the V-shaped inclosure and are trapped by 75 the contact faces 27, the shoes 29 being forced against the wheels of the train while the plates 16 are drawn forward on the plates 19 by the movement of the train.

This forward or longitudinal movement 80 of the plates is utilized to operate the rear end of the brakes and so secure the application of the full length of the latter upon the train as will now be described. Chains or the like 100 are attached to each of the front 85 extensions 17 of the plates 16, and extend therefrom through suitable guides 101, and preferably merge into a single length 100^b which pass over pulleys 102 to the top of the piston rod 103, to which they are attached. 90 The piston rod 103 projects from the top of a hydraulic casing 104 having a partition 104^a therein, near the bottom and forming a compression chamber 105 while an air compression chamber is formed at the top of the 95 casing by placing the normal level of the fluid below the latter and if desired a loose partition 106 may be floated upon the fluid. The piston rod 103 carries two heads, one of which 107 is located in the fluid chamber and 100 the other 108 in the bottom resistance chamber, such heads being normally at or near the bottom of their respective chambers.

In order to offer a high resistance to the pulling up of the piston 103, I prefer to provide the bottom resistance chamber with vertical webs 109, extending inward from the side of the chamber and being tapered or gradually reduced in radial extent from the top to the bottom as shown at 100, the head 108 being cut away as at 111, to accommodate the webs. By means of this construction the capacity of the bottom chamber is gradually decreased toward the top and therefore a gradually increased resistance is offered to the piston head as it approaches the top of such chamber. The fluid casing 104 is connected to a casing 112 by a pipe 113 and when the piston 103 is pulled up by the chains 100 pressure is 110 transmitted to this casing 112 to operate the rear end of the plates 16 in a similar manner to their front ends, by the casing 115. The casing 112 has for this purpose a rack 114 and gear wheel 115, attached 115 in operative manner to drums 116 in a housing 117 and adapted to wind cables 118 attached to arms 119, which are similar to the arms 20, 20^a and 21 and 21^a, being pivoted at 120 upon brackets 121 and slidably at 130

tached to the plates 16 by blocks 122, and ball bearings as previously described in connection with the arms 20, 20^a and 21 and 21^a.

To apply the brakes in a gradual manner, 5 I provide means for momentarily relaxing the latter and thus permitting the rails 28 of the shoes 29 to advance within the V-shaped inclosure before they are again trapped, the train being thus gradually 10 brought to a standstill. I secure the above result by providing the casing 112 with an auxiliary chamber 124 communicating at one side therewith and having a pipe 125 leading therefrom to the pipe 113 at a point below the chamber 124. A valve 126 opening 15 by pressure in the chamber 124 is located in the latter adjacent to the casing, while a gate valve 127 controls the communication 20 between the auxiliary chamber and the casing. The valve 127 is connected by a slide- 25 able arm 128 to a piston 129 in an air cylinder 130, which latter has an air supply pipe 131, leading thereto from the air chamber at the top of the chamber 104. A branch pipe 132 leads from the pipe 131 to the said top air chamber, the openings of these pipes into the air chamber being normally closed 30 by the valves 133 and 134 respectively. The valve 133 in the pipe 131 opens upon a pre-determined pressure in the air chamber while a pressure in the branch pipe opens the valve 134 therein.

When the train is first trapped by the 35 brake and the plates 16 of the latter drawn forward the piston 103 will be pulled up, the main resistance being exerted in the resistance chamber 105. The upward movement of the piston head 107 creates a fluid pressure which is transmitted through pipe 40 113 to the casing 112 and forces the piston 34^a up, thereby operating the arms 119 to apply the brakes as before described. Simultaneously with the action just described, the air is compressed at the top of the casing 45 104 and when the pressure reaches a pre-determined point the valve 133 is opened and the brakes released. The pressure in the top of the chamber being immediately reduced the valve 133 closes and the brakes 50 applied as before. The action of the momentary release is as follows: The air pressure passes from the top chamber through pipe 131 to the cylinder 130 and raises the piston 129, which in turn raises the gate 55 127 and permits a portion of the fluid in the casing 112 to flow into the auxiliary chamber 124. The fluid level in casing 112 being lowered the piston 34^a drops a corresponding distance. In falling the weight 60 of piston 34^a revolves the drums backwardly allowing a partial unwinding of the cables 40-42, thus releasing the arms 119 sufficiently to relieve the pressure of the plates 16 upon the shoes 28-29. The plates 28-29 65 being now free from the grip on the train

the plates 16 lack the pull necessary to cause further action in cylinder 104, consequently piston 103 falls, due to gravity plus air compression in the head of the cylinder 104, weight of water on piston-head 107 and 70 the partial vacuum caused by piston 103 having ascended into the chamber 104, from the resistance chamber 105; these combined forces drawing back the plates 16. The falling of the piston 103 increases the capacity 75 of the cylinder 104, and suction takes place drawing off the fluid from the chamber 112 and 124 and the cylinder 15, (following brake) also further unwinding cables 40 and 42 by permitting piston 34^a to fall a greater 80 distance than was allowed by the fluid passing through valve 127.

The relaxing of the brakes is only momentary because as soon as the air at the top of the casing 104 expands and the pressure consequently drops below the predetermined point the valve 133 closes and the piston 129 and gate valve 127 drop by gravity the air exhausting from cylinder 130 through the branch pipe 132, past the valve 90 134 into the top of the casing 104. The fluid from the auxiliary chamber drains into the main 113 through pipe 125.

When the shoes 29 again engage with the plates 16 the full pressure is applied once 95 more as described, the relaxation of the brakes taking place intermittently until the speed of the train has been reduced to such an extent that the pull upon the piston is not sufficient to produce the predetermined 100 pressure at the top of the casing 104.

It is desired to positively hold the arms 20, 20^a and 21 and 21^a in operative position and to utilize the forward movement of the plates 16 to help to draw these arms 105 104 and the plates 16 toward each other. Accordingly I have provided shafts 140 each being rotatably mounted in brackets 141 upon the inner side of one of the brake operating arms 20 and 20^a and 21 and 21^a and having 110 a gear wheel 142 mounted at the upper end thereof, and a spool 143 at the lower end. The gear wheels 142 each engage with a rack 144 formed upon or attached to, the underside of each of the plates 16, while one end of a cable 145, is attached to each of the spools 143, each of the cables extending from the spool upon one arm to the opposite arm on the other side of the track.

The forward movement of the plates 16 causes the spools 143 to wind the cables 145 thereon, and so draw the arms 20, 20^a and 21, 21^a toward each other, and to prevent straining of such cables I have partially 125 stripped the gear wheels 142 (see Fig. 9). The location of the stripped portions being such that when the cables have been wound upon the spools to a sufficient extent to draw the arms tightly upon the shoes 29, 130

the stripped portions of the gear wheel will be presented to the rack and the rotation of the spools stopped. Fingers 150 upon the shafts 140 are adapted to engage with 5 the operating arms at the time the stripped portions of the gear wheel will be presented to the rack and the rotation of the spools stopped. Fingers 150 upon the shafts 140 are adapted to engage with the operating 10 arms at the time the stripped portions of the gear wheels are presented to the rack and prevent any further accidental rotation of the shafts 140.

To act in conjunction with the means for 15 momentarily relaxing the brakes and to permit such action I provide means whereby the cables 145 are partially unwound from their spools simultaneously with the partial unwinding of the cables 40 and 42; the 20 above mentioned means consists preferably of spools 151 carried by the shafts 140, in addition to the spools 151, having cables 152 attached thereto and extending therefrom to the arm 128; these cables are omitted 25 from the left hand Fig. 8 to avoid confusion. The cables 152 are normally slack and adapted to be wound upon their spools and made taut at the same time as the winding of the cables 145. The cables 152 are attached to the arms at 153 and pass under pulleys 154 located at a point below the lowermost position assumed by the point of attachment 153 by the movement of the piston 129, and by this arrangement the upward 30 movement of the latter will exert a pull upon the cables 152, and partially unwind the shafts 140. This also unwinds the cables 145 a sufficient amount to permit of the relaxation of the operating arms. The 35 unwinding of the cables 152 and the necessary rotation of the gear wheels 142 in an opposite direction are permitted by the partial backward movement of the plates 16.

It may be desired to release the brakes before 45 the expiration of the period during which they hold the train; for this reason I provide a housing at a suitable point near the track and inclosing a spring drum 156 which is operated by a crank 157 geared 50 thereto as at 157^a. A cable 158 is connected to a spring drum at one end and the opposite end is connected to the arms 128. A similarly constructed spring drum 159 operated by a crank 160, is connected to the 55 piston rod 35 by a cable 161, the two drums being distinguished from each other by some suitable mark such as No. 1, for housing 155 and No. 2, for the housing inclosing drum 159. The shaft 162 of the drum 159 extends 60 through one end of the housing and has a pointer 163 thereon while such end of the housing constitutes a dial having thereon numbers 1 and 2 representing the housings.

65 When under ordinary operative conditions

the piston 34 is raised to set the brake the cable 161 is slackened and the spring drum 159 permitted to rotate and cause the pointer 163 to indicate the raised position of the piston by pointing to No. 1 on the dial. Under 70 different conditions when the safety device drains the cylinder 15 and allows the piston 34 to drop and so set the brake, the consequent unwinding of the cable 161 from the drum causes the pointer to indicate the 75 lower position of the piston by pointing to No. 2 on the dial. When No. 1 is indicated upon the dial it will be known that to release the brake it will be necessary to wind the drum so designated, the result being 80 that the gate 127 will be raised and the level of the piston 34 lowered to the normal point and the brakes released, while the indication of No. 2 upon the dial will call for the winding up of the piston 34 to its normal 85 level and the release of the brakes. As before mentioned the brake mechanism just described is duplicated along the track so as to act upon the full length of the train (see A, B, C, Fig. 10) it being preferred to make 90 each of the plates 16 of a length to engage with the wheels of one car or longer.

When connected in series the casing 112 of the last brake A is connected to the piston 15 of the preceding brake B by a pipe 170 while the rear extension 17^a of the plates 16 in the last brake A are operatively connected as at 171 to the piston rod 103, of the brake B in addition to the connection 100 between the front extension 17 of the brake B and such 100 piston rod, although it will be apparent that the use of this connection 100 is only essential with the last brake A. The connection between the brakes is the same throughout the series, so that when brake A, connected by the pipe 14^a, to the setting device has been set, and a train engages therewith as previously described, the whole series will be operated for the reason that when pressure is created in the casing 112 of each 110 brake such pressure will be transmitted through the pipe 170 to the casing 15 of the preceding brake.

As indicated in the preceding paragraph, the brake is connected in series A, B, and 115 C, etc. There may arise occasions where one or the other may be rendered useless owing to the breakage of some essential part. To prevent the whole series from becoming useless, I provide means whereby the one 120 of the series which is useless falls out of action, and in doing so causes a setting of the following portion of the series, thereby providing for contingencies. To obtain this result I construct on the conduit 113, a duct 125 172, normally closed by a slide valve 180, lying parallel to the conduit 113. The slide valve 180, operates within a pipe communicating at both ends with chambers as 175 and 176. To hold the slide valve 180 in 130

position over the duct 172 and to supply the force to operate the valve 180 I place on both sides of the valve 180, a fluid, which remains between the slide valve 180 and the 5 chambers 175 and 176. In the chambers 176 and 175 is placed a floating piston head 182 and 184. The piston head 182 is of greater weight than the floating piston 184; it is therefore apparent that the slide valve 180 10 will be forced toward the chamber 176. To prevent this the floating piston 182 is held suspended by a cable which may be attached to any portion of the mechanism desired. In the present case it is attached to the arm 15 of the brake 20, 21^a. The pressure of the floating head 184 on the fluid will now hold the slide 180 in place over the duct 172. The head 182 is attached as aforementioned to a moving arm 20, of the brake. The head 20 182 therefore will move upward and downward on the movement of the said arm 20. To prevent the duct 172 being uncovered in this case I make the slide valve 180 of sufficient length to allow for the limited movement. In the event of the duct being uncovered due to the pulling up or the falling of the cable 183, which would take place on the withdrawal of the arm 20 or the breaking of the arm 20, the slide valve 180 25 30 would be forced one way or the other uncovering the duct 172, allowing the fluid contained in conduit 113 to flow into the chamber 177, through the passage comprising the duct 172. To prevent the fluid contained between the heads 182 and 184 from escaping during the uncovering of the duct 172 I provide the slide valve 180 with reduced portions 173 and 179, which reduced portions take up a position above the duct 172 allowing the fluid from conduit 113 to pass to the chamber 177, and through the discharge port 178 without interfering with the fluid contained behind the heads 181 of the slide valve 180. 45 It should be noted that this slide valve can be attached to any conduit which communicates with a setting chamber 15, viz., conduit 113 as shown, conduit 14^a, or 170, etc. The effect of this valve is seen when 50 it is called to mind that the setting of the brake is obtained in the two ways, the forcing up of the piston 34 of the following brake of the cylinder 15, or the falling of the piston 34 cylinder 15. 55 It is here reiterated that the length of the gear on the rod 114 is such that when the casing 112 is drained this gear will drop out of engagement with the drums. Stops may be placed where convenient to prevent 60 the piston 34^a falling too far within the cylinder 112. The reason for this is to prevent the gears unwinding the drums and then rewinding the cable thereon in an opposite direction and so obtaining the closing of the back part of the brake as ex-

plained in reference to the front part of the brake. The rear of the brake should only be operated by the cables winding one specific way.

I will now refer back to the description given of the action for the setting of the following brake, due to the operation of the chamber 104. It will be seen that the piston 103 is drawn up and the fluid forced along pipe 113 to casing 112; also along conduit 170 to casing 15 of the preceding brake. It is desirous that regulation be placed upon the casing 15 of the following brake when suction takes place on the falling of piston 103. A valve 212 is placed on the pipe 170 between the casing 112 and the casing 15. This valve is to allow most of the head in the chamber 124 to pass back to chamber 104 and also prevent the chamber 15 passing too much of its fluid back to chamber 124. To accomplish this I provide the valve 212 to operate both by suction and pressure. The fluid from 104 forces a slide valve 217 to uncover a bypass 213 which communicates from port 212 to bypass 213 and so to pipe 170, farther along and pass the partition 214. The slide 217 is held in position by a spring which is such that the slide has freedom to move to compress the spring 218 and also to extend same. Normally the slide 218 lies directly across the mouth of the bypass 213 thereby preventing direct communication between each side of the partition 214; when the pressure from 104 is lowered as when suction takes place, the spring will be elongated and as the fluid will not have passage through 212, I provide a further bypass 215 leading from the mouth of bypass 213 to conduit 170. It has already been explained that it is not desirous to obtain too much fluid from cylinder 15 brake B, on the return suction, therefore I make the bore of the bypass to port 215 smaller than the bore of 170 or bypass 213. The small bore in the partition 214 allows of drainage from cylinder 15 on the action of slide valve 180 placed to drain the mechanism 15 brake B, on the breakage of parts which allows piston 34 to fall and first unwind the cables and then rewind same upon the drums 38. 110 115

What I claim is as follows:—

1. In a device of the character specified, the combination with a device to be operated, of a hydraulic mechanism operatively connected to said device, a setting device spaced from the hydraulic mechanism and adapted to set said mechanism in operative position and means for automatically setting such mechanism upon the disorganization or removal of a part or parts of the setting device. 120 125

2. In a device of the character specified, the combination with a device to be operated, of a hydraulic mechanism operatively 130

connected to said device, a setting device spaced from the hydraulic mechanism and connected therewith by a conduit provided with valves and means for automatically setting said mechanism upon the disorganization of a part or parts of the latter.

3. In a device of the character specified, the combination with tracks of a hydraulic mechanism operatively connected by conduit to said tracks and means for automatically setting said mechanism upon the disorganization of a part or parts of the tracks.

4. In a device of the character specified, the combination with a device to be operated, of a hydraulic mechanism operatively connected to said device, a setting device connected with the hydraulic mechanism and adapted to be operated by a train and means controlled by the train for making the hydraulic mechanism unresponsive to the action of the train upon the setting device.

5. In a device of the character specified, the combination with a brake at the side of the track and normally out of the path of the train, of a hydraulic mechanism operatively connected to the brake, a setting device spaced from the hydraulic brake, and adapted to set the brake, such hydraulic brake including means for further setting the brake by engagement of the train with the brake.

6. In a device of the character specified, the combination of a hydraulic mechanism, a setting device spaced from the hydraulic mechanism and adapted to be engaged by a train, such hydraulic mechanism including means operated by the setting device for applying the brake and adapted to be operated by the engagement of a train with the setting device, and means for intermittently releasing the pressure of the brakes by a predetermined pressure.

7. In a device of the character specified, the combination with a brake at the side of the track, and normally out of the path of the train, of a hydraulic mechanism for setting the brake, including a fluid casing having a piston therein operatively connected to the brake, such fluid casing being adapted to receive a pressure fluid therein whereby the piston is operated to set the front portion of the brake in a position to enable the car to advance fully into the brake before the complete action of the brake.

8. In a device of the character specified, the combination with a brake at the side of the track and comprising a pair of members normally out of the path of a train and having a movement longitudinally of the track, of brake setting means including a fluid casing located at a distance from the brake; a piston in the casing and adapted to be depressed by a train; a second fluid casing located adjacent to the brake and communi-

cating with the first casing; a piston in the second casing and operatively connected to the brake; and brake applying means including a resistance chamber inclosing a piston, such piston being connected to the brake and adapted to be operated by the longitudinal movement thereof; and a fluid casing communicating with the fluid resistance chamber and having a piston therein operatively connected to the brake.

9. In a device of the character specified, the combination with a brake at the side of the track and having a limited movement longitudinally of the track of a hydraulic mechanism for operating the brake and including a casing; a piston in the casing; and operatively connected to the brake, a second casing including a resistance chamber of increasing resistance from bottom to top, and a fluid chamber in communication with the first casing; and a double headed piston in the second casing and having one head located in the resistance chamber and the other head located in the fluid chamber such double headed piston being connected to the brake and adapted to be moved by the longitudinal movement of the latter and means controlled by the double headed piston for applying the brake.

10. In a device of the character specified, the combination with a brake at the side of the track and having a movement longitudinally of the latter, of a hydraulic mechanism for operating the brake and including a casing having a piston therein operatively connected to the brake, such casing being adapted to receive a pressure fluid therein to raise the piston and apply the brakes; and means for intermittently releasing the pressure in the casing and correspondingly releasing the brakes, including an auxiliary chamber communicating with the casing, a valve controlling the communication between the casing and auxiliary chamber, an air cylinder, a piston in the cylinder and connecting to said valve, a second casing having an air compression chamber, a conduit leading from the air compression chamber to the air cylinder, a valve in said conduit adapted to automatically open upon a predetermined pressure in the air compression chamber, a branch pipe leading from the conduit to the air compression chamber, a valve in said branch pipe adapted to be opened upon a predetermined pressure in the branch pipe and a piston in said second casing, connected to the brake and adapted to be moved by the longitudinal movement of the latter and compress the air in the compression chamber.

11. In a device of the character specified the combination with a pair of members at the side of the track, and adapted to be moved toward each other and having a movement in the longitudinal line of the

- track, of means for operating said members, including pairs of arms pivoted at the bottom and slidably attached to the members at the top, a fluid casing adjacent each pair 5 of arms, a pair of drums rotatably supported above each casing, a cable wound upon each of the drums and attached to one arm of each pair, a gear wheel rigidly connected to and mounted in axial line with each pair 10 of drums a piston inclosed by each of said casings and including a rack-like rod extending through the top of the casing and engaging with the said gear wheel, an operating casing having a fluid chamber communicating with one of said fluid casings, a piston 15 in said operating casing, attached to the longitudinally movable brake members and adapted to be moved thereby to create a compression in the fluid chamber and the 20 casing communicating therewith and a setting device spaced from the brake and operatively connected with the other of said casings.
12. In a device of the character specified, 25 the combination with a device to be operated, of a hydraulic mechanism for operating such device and means for setting the hydraulic mechanism including separate, compressible rail portions inclined inwardly and 30 upwardly toward each other, a casing below the rail portions and including an air chamber and a fluid chamber the latter in communication with said hydraulic mechanism, a double headed piston in said casing having 35 one head located in the air chamber and the other head in the fluid chamber, the rod of such piston having the inclined rail portions resting thereon.
13. In a device of the character specified 40 the combination with a device to be operated, of a hydraulic mechanism for operating such device and means for setting the hydraulic mechanism including separate compressible rail portions inclined inwardly and 45 upwardly toward each other, a casing below the rail portions and including an air chamber and a fluid chamber, a piston in said casing, the rod of said piston having the inclined rail portions resting thereon, a conduit 50 leading from the fluid chamber to the hydraulic mechanism, an auxiliary chamber communicating with said fluid chamber, a valve normally closing the communication between the auxiliary chamber and the fluid 55 chamber and adapted to open upon pressure in the former, a pipe leading from the auxiliary chamber to the fluid chamber, a gate valve normally closing said pipe, a normally open gate valve applied to said conduit and 60 means connected to said gate valves and adapted to be engaged by a train to simultaneously open and close said valves, respectively and for returning same to their normal positions.
- 65 14. In a device of the character specified,
- the combination with a device to be operated and located at the side of a rail, of a hydraulic mechanism for operating said device and means for setting the hydraulic mechanism including a pair of rail portions set in 70 the rail, each being pivoted at one end adjacent to the main portion of the rail and inclined toward each other, a casing below the rail portions and communicating with the hydraulic mechanism, a piston in said casing, the rod of which has the inclined portions resting thereon and has a duct leading up therethrough from the fluid casing to the exterior of the latter, a weighted valve controlling said duct and means for normally holding said valve in closed position and adapted to be acted upon to permit the valve to open.
15. In a device of the character specified 75 the combination with a device to be operated, of a hydraulic mechanism for operating one of such devices, including a fluid casing 112, a floating piston in the fluid casing operatively connected to said device, a pipe 113 for supplying the fluid under pressure to said fluid casing, means for operating another of said devices, including a fluid casing 15 communicating with the first fluid casing 112 by a pipe 170, a floating piston 80 34 in the last mentioned fluid casing and connected to the other of the said devices, which latter is adapted to be operated by both an upward and a downward movement of such piston in its fluid casing 15 and means 212 for regulating the fluid level in 85 the said fluid casing 15 including a draining partition 214 communicating with said fluid supply pipe 170, and a valve 210 to control the passage of the fluid to and from the said fluid casings.
16. In a device of the character specified 90 the combination with a device to be operated, of a hydraulic mechanism for operating the device, a pipe communicating with the mechanism, a plunger normally closing a port in said pipe, a casing at each end of the plunger and being operatively connected with the plunger, pistons floated at each end in the aforesaid casings and adapted to hold the plunger over the port through a limited movement of the plunger, a drainage port, the plunger normally closing the drainage port, and adapted on the movement of the pistons to place said ports in communication to drain the fluid from the mechanism.
17. In a device of the character specified, 95 the combination with a device to be operated, of a hydraulic mechanism for operating the device, and means for setting the hydraulic mechanism including separate compressible rail portions, inclined inwardly and upwardly toward each other, a casing below the rail portions and including an air chamber and a fluid chamber, a piston in said 100 casing, the rod of said piston having said 105

- 130

inclined rail portions resting thereon, a fluid casing spaced upon the rail portions, a conduit leading from the fluid chamber to the fluid casing, a valve normally closing the conduit, a drainage port adapted to gradually release the fluid in the casing, a piston floated in the fluid casing, a rod with rack operatively connected to the piston and adapted to engage with said device.

18. In a device of the character specified the combination with a setting device to be operated, a casing, a floating piston having a limited movement in the casing, a rod with a head slidably connected to the floating piston, with pivoted means held in connection with head, and operatively connected to the setting device, a conduit containing fluid and connected to the tracks, the said tracks holding suspended within themselves the aforementioned fluid, whereby the setting device is operated on releasing of the fluid from the tracks.

19. In a device of the character specified, the combination with a hydraulic mecha-

nism, a setting device casing 15, an auxiliary chamber 185 having communication therewith, valves 187 and 194 controlling communication between said casing and chamber, means normally holding the valve 187 closed, means for releasing said holding means to admit fluid from the cylinder 15 to chamber 185, a piston 193 in chamber 185, a conduit connected with chamber 185 at the opposite side of piston 193 from the aforesaid valve mechanism, a pneumatically operated lock 198 to hold valve 194 and prevent communication from chamber 185 to casing 15, a conduit connecting the chamber 185 with said lock, and a valve 195 to admit air to the chamber 185, for the purpose described.

April twentieth, nineteen hundred and fourteen.

LEONARD HEALD.
